[57] CLAIM

The ornamental design for a cutting tool holder, as
shown and described.

DESCRIPTION

FIG. 1 is a top, front, and right side perspective view of
a cutting tool holder showing my new design;

FIG. 2 is a top, front, and left side perspective view
thereof;

FIG. 3 is a bottom, front, and left side perspective view
thereof.

The rear end view is flat and unornamented.
